MEDICAMENT CONTAINER HAVING SCALE-REMOVING ABRASIVE

Irving B. Wershaw, New York, N.Y., assignor, by mesne assignments, to Dome Chemicals, Inc., Indianapolis, Ind., a corporation of Indiana

Application March 7, 1958, Serial No. 719,864

1 Claim. (Cl. 128—260)

This invention relates to containers for medicaments employed in the treatment of psoriasis and other scale forming skin diseases, which containers are constructed and designed to enable them to be used to effect removal or aid in the removal of scales on the skin before the medication is applied.

It is among the objects of the present invention to provide a container for medicament, which container is shaped to permit holding thereof in the hand of the user, having at one end a dispensing opening for the medicament and at the other end an abrasive member which can be used to effect removal or aid in effecting the removal of scales.

It is another object of this invention to provide such container carrying a scale-removing abrasive member, which container and member cooperate to permit their conjoint use for effecting removal of skin scales and moving the medicament contents within the container so that such contents are disposed relative to the dispensing opening to be in position for application to the infected skin from which the scales have been removed by the abrasive scale-removing member.

For a fuller understanding of the nature and objects of the invention, reference should be had to the following detailed description taken in connection with the accompanying drawing, in which:

Figure 1 is an exploded perspective view showing the component parts of the medicament container having a scale-removing member embodying the present invention, in which figure the housing of the container and a portion of the medicament holder are broken away to show their interior structure;

Figure 2 is a perspective view of the medicament container having thereon the scale-removing member embodying the present invention; this figure shows the container open, i.e., without the closure cap;

Figure 3 is a vertical section through an embodiment of the present invention; and

Figure 4 is a horizontal section taken in a plane indicated by the line 4—4 on Figure 3.

In the drawing, 10 indicates a housing of the container, which housing in the embodiment of the invention shown consists of a cylindrical outer wall having on its interior spaced re-enforcing flat ribs 11. These ribs 11 extend substantially the full length of the cylindrical wall of housing or casing 10. Housing 10 is of a length such that it can be conveniently held and firmly held in the palm of the hand of the user. End 12 of this housing desirably is provided with a circular rib or projection 13 over which a cap 14 of polyethylene or other suitable flexible material may be snapped to provide a closure for the dispensing end 12 of the container. The other end 15 of the housing is provided with a closure wall 16 having a central opening 17.

Secured to wall 16 is a bearing 18 in which is mounted for rotation a threaded member 19. Member 19 is firmly held by the groove 21 therein cooperating with the projection 22 on the bearing member 18 so that it is

2

free to turn but not to move in a longitudinal direction. Member 19 is threaded for substantially its full length and extends from a point 23 exteriorly of the closure wall 16 to near the top of the dispensing end 12 of the housing 10. Desirably, the exterior end of the threaded member 19 has formed integrally therewith or fastened thereto a knurled member 24 to which is secured an abrasive disc 25. Abrasive disc 25 may be of soap-stone, carborundum, lava stone or other suitable abrasive material effective to remove scale from skin. Preferably, disc 25 is of frusto-conical shape having the side walls 26 slightly inclined from the end 27 of maximum diameter towards the opposite end 28, which is fastened, as by a suitable adhesive or cement, to the knurled member 24.

Mounted for up and down movement on the threaded member 19 is the medicament holder 28, desirably in the form of a metal, preferably aluminum or steel, shell, having struck from the side walls fingers 29 which enter the body of medicament and firmly anchor it to the holder 28. The base 31 of the medicament holder 28 is provided with a threaded boss 32, which is arranged to threadedly engage the threads on the periphery of member 19. Thus, when member 19 is rotated by turning either the knurled member 24 or the abrasive disc 25 the medicament holder 28 moves up or down within housing 10, depending upon the direction of rotation. The side walls of the medicament holder 28 are flattened at spaced points to register with the ribs 11, thus maintaining the medicament holder 28 in housing 10 at all times so that it is free to move up and down but not to rotate.

In use of the medicament container the housing 10 is firmly grasped in the hand of the user, with the abrasive disc 25 exposed. The user can rub the side walls 26 of the abrasive disc or the top end 27 thereof against the scales on the skin, to aid in the removal or effect the removal of such scales. In the case of scales exceptionally tenacious, the sharp edge provided at the circular periphery where the top end 27 intersects the side walls 26 can be employed.

It will be noted that in using the abrasive member 25 to effect removal or aid in the removal of scales, it is rotated due to friction between the scale or skin and this abrasive member, causing rotation of member 19 to move the medicament holder 28, thus forcing the medicament contents 33 against the cap 14 so that the contents 33 are in dispensing position as soon as the cap is removed. After the scale has been removed, the medicament can be applied to the exposed skin. If necessary, either the knurled member 24 or the abrasive member 27 can be further rotated to feed the medicament through the dispensing opening onto the skin.

Housing 10 and knurled member 24 may be of plastic, metal or other suitable material of construction. It may be of any desired relatively elongated shape including circular, rectangular or other polygonal shape in cross section.

It will be noted that the present invention provides a container for medicaments shaped to permit holding thereof in the hand of the user, having at one end a dispensing opening, and at the opposite end an abrasive member which can be used to effectively remove or aid in effecting the removal of skin scale. In use, this abrasive member cooperates with the medicament holder to position the medicament for ready application to the skin once the scale has been removed.

From the foregoing, the embodiments of my invention will be fully understood, but it is to be understood that the invention is not restricted to the present disclosure to any extent otherwise than by the manner in which such invention is claimed.

What is claimed is:

A container for medicament for the treatment of psoriasis and other scale-forming skin diseases, consisting of a substantially cylindrical container longitudinally elongated and of a length such that it can be firmly grasped in the palm of the hand of the user and adapted to contain a medicament, said cylindrical container having a plurality of longitudinal spaced ribs on the inner walls thereof, which ribs have substantially flat surfaces, and having a dispensing opening at one end and a closure wall at the other end provided with a central opening, a bearing having a central opening mounted in the interior of said container on said closure wall with the opening therein smaller than and aligned with the opening in said closure wall, a medicament holder within said container having the side walls thereof flattened to register with the flat surfaces on said ribs and having at least one finger struck from said side walls adapted to enter the body of medicament and firmly anchor it to said holder, a threaded member having its periphery

threaded substantially the full length thereof extending from the exterior of said closure wall to near the opposite end of said container, said member being grooved to fit within the central opening in said bearing to permit rotary but not longitudinal motion thereof, said medicament holder being in threaded engagement with said threaded member, and an abrasive disc secured to the end of said threaded member to effect rotation thereof, said disc extending exteriorly of said closure wall.
